AWNING FOR CLOSED CARS

Filed Aug. 10, 1926

By *Watson E. Coleman*
Attorney

UNITED STATES PATENT OFFICE.

LAWRENCE M. CROW, OF WACO, TEXAS.

AWNNG FOR CLOSED CARS.

Application filed August 10, 1926. Serial No. 128,435.

This invention relates to awnings or shades for the windows and doors of closed cars and particularly to windows or doors having vertically sliding panes or sashes.

5 The general object of the present invention is to provide an awning structure which may be readily applied to a door or window frame and whose simplicity is such that the awning may be readily shifted or changed 10 from one window or door opening to another without any trouble.

A further object is to provide an awning attachment of this character which will permit the closing or opening of the pane or 15 sash without having to remove the awning.

My invention is illustrated in the accompanying drawings wherein:—

Figure 1 is a perspective view of a portion of an automobile showing my invention applied thereto;

Fig. 2 is a vertical sectional view through the upper portion of an automobile door opening showing my awning in section;

Fig. 3 is a transverse sectional view on 25 the line 3—3 of Figure 2;

Fig. 4 is a perspective view of the awning frame.

Referring to these drawings it will be seen that the awning frame consists of a 20 transverse upper rod 10 which is rounded at its ends, a transversely extending lower rod 11 and the downwardly and outwardly extending rods 12 which are disposed inward of the ends of the upper rod 10. An awning 35 13 of any suitable material is stitched or otherwise connected to the upper and lower rods.

For the purpose of holding the awning in a downwardly and outwardly extending 40 position when the device is applied to a door opening I provide the rearwardly extending supporting arms 14 preferably made by bending the rods 12 at their lower ends and extending these rods rearward. These rods 45 extend rearward any suitable distance and are then angularly bent as at 15 and this bent portion 15 is flattened, an important feature.

In putting this device upon a car, place the ends of the upper rod 10 in the felt lined grooves where the glass pane or sash operates, putting this rod very close up to the top of the window opening. The arms 14 may then be sprung inward to pass the frame of the window and the lateral projections 15 are forced outward by the resiliency of the arms to a position between the outermost felt layer and the steel portion of the door, as shown in Figure 3. Because these projections are flat they will offer no obstruction to the raising or lowering of the window glass or sash and hence the awning does not have to be removed in order to secure this result.

The simplicity of my awning not only 65 renders it very cheap but makes it possible to readily change the awning from one door or window of a car to another with very little trouble.

I claim:—

An awning for the door or window openings of motor cars comprising a transversely extending upper rod, end rods rigid with and extending downward from the upper rod inward of the extremities of the upper 75 rod, a lower transverse rod rigid with relation to the end rods and connecting the same, and supporting resilient arms extending rearward from the lower ends of the end rods and rigid therewith and at their extremities angularly bent and flattened whereby the extremities of the upper rod and the flattened ends of the arms may be inserted in engagement with a window casting with the ends of the upper rod disposed 80 within the felt lined groove of a window sash and the flattened extremities of the arms adapted to be inserted between the felt lining of said groove and the wall of 85 the groove.

In testimony whereof I hereunto affix my signature.

LAWRENCE M. CROW.
